UNITED STATES PATENT OFFICE.

BENJAMIN P. FORTIN, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,277,399.

Specification of Letters Patent.

Patented Sept. 3, 1918.

Original application filed January 12, 1916, Serial No. 71,606. Divided and this application filed June 19, 1917. Serial No. 175,578.

To all whom it may concern:

Be it known that I, BENJAMIN P. FORTIN, a citizen of the United States, residing in Hartford, in the county of Hartford and 5 State of Connecticut, have invented certain new and useful Improvements in Type-Writing Machines, of which the following is a specification.

This invention relates to typewriting machines and more particularly to means for accurately guiding the sheets while in the machine.

This invention is an improvement on a machine of the type shown and described in 15 the patent to Wernery and Smith, 1,132,055, dated March 16, 1915, in which the fan-fold web advances over an auxiliary carriage, and then over a carbon-retracting carriage, where the plies of the web are interleaved 20 with carbon sheets, the latter being carried by the carbon-retracting carriage. The web advances thence over a paper table and around the platen, and then to a paper shelf at the delivery side of the platen.

25 A feature of this invention is the provision of means whereby the sheets may be accurately gaged and guided during the entire travel through the machine, particularly at critical points in said travel.

30 The auxiliary paper table at the intake side of the machine is provided with a pair of upstanding fingers or side-edge gages, between which the leading end of the web advances.

35 To guide the web proper into register with the carbon sheets, the carbon-retracting carriage is provided with guides which engage the side edges of the folded web just before the web is interleaved with the carbon sheets.

40 After a portion of the web has been written upon, the platen is lifted, to straighten out the webs to permit the retraction of the carbons. The web sheets are then pulled 45 forwardly by hand until the leading edges thereof meet a gage extending up from the paper shelf at the delivery side of the machine. This gage determines the location

of the bottom edge of the written form, which may thereupon be severed from the 50 web by means of a knife.

To aid the operator in accurately alining the bottom edge of the written form with the knife, a gage is provided upon the auxiliary paper shelf. This gage is arranged 55 to be engaged by the side edge of the paper, before the written form is severed from the web.

When the carbon sheets are relieved from pressure by the shifting of the platen, the 60 carbon carriage is moved rearwardly to bring the interleaved carbon sheets thereon into coöperation with a fresh portion of the web. During this movement, the guides arranged thereon, jog the web into proper 65 superposed relation with the carbon sheets.

Another feature of this invention is the provision of the novel arrangement and construction of these various gages, whereby 70 they may be economically manufactured and readily attached to the machine, and so that adjustment may be made for the purpose of permitting forms of various dimensions to be used.

Another feature is the provision of one of 75 the guides at the introductory side of the machine, with means whereby it may also be used to grip the web and prevent the same from falling off the machine. This combined guide and gripper is adjustable to accommodate webs of various widths.

This application is a division of my co-pending application, Serial No. 71,606, filed January 12, 1916 (now Patent No. 1,237,319, dated August 21, 1917). 85

Other features and advantages will hereafter appear.

In the accompanying drawings, Figure 1 is a perspective view of the invention as applied to an Underwood type-writer machine.

Fig. 2 is a cross sectional view of the locking device for the web-holding finger at the rear of the table.

Fig. 3 is a side elevation, partly in side 95 elevation and partly in cross section,

Fig. 4 is a perspective view of one of the adjustable lateral gages or guides for the web, located on the holder of Fig. 3.

Fig. 5 is a perspective view of the gage 5 or guide on the paper shelf for alining the web before the same is cut.

Referring to the drawings, the platen 10 has an axle 11 which is journaled in a frame having end pieces or arms 12 fast to a rock-
 10 shaft 13. The shaft 13 is journaled in the end plates 14 of the platen carriage. The frame for which the shaft 13 serves as a pivot, is normally held in Fig. 1 position, with the platen down against the usual feed
 15 rolls 15 and 16. It is swung from its normal or printing position, as shown in the patent to Wernery and Smith, No. 1,132,055, by means of an arm or handle 17, which latter is also fast to the shaft 13. For lock-
 20 ing the platen frame in printing position, the handle 17 carries a pin 18 adapted to be engaged by a hook 19 pivotally mounted on a bracket 20 on the left-hand end plate 14 of the platen carriage. A spring 21 en-
 25 gages the hook and the bracket to hold the hook in platen locking position, and to return the hook to such position when free to do so. The nose of the hook is shaped at 22 to permit the pin 18 to cam it backward
 30 until the pin can pass under the nose, thereby making the locking operation automatic when the platen frame is swung down to normal position. A tooth 23 on the hook may serve to determine the return throw, and normal position of the platen, in con-
 35 junction with a pin or stop 24 on the right-hand end carriage piece 14, against which the arm 12 strikes when the platen is thrown down.
 40 To effect the line-space feed or rotation of the platen, there are provided the usual hand wheel 25 and ratchet wheel 26, both fast to a short shaft 27, mounted to rotate in the left-hand end piece 14 of the carriage.
 45 In printing position, the shaft 27 is concentric with the platen shaft 11. The ratchet 26 is actuated by a pawl 28 on a slide 29 which may be operated, as in Underwood typewriting machines, by a line-
 50 space lever (not shown). A spring pawl (not shown) holds the ratchet wheel and platen against accidental displacement. The driving connection between the shaft 27, whose axis does not shift, and the platen
 55 axle 11, which swings from one to another position, consists of gears 30, 31 and 32. The gear 30 is fast to the shaft 27; the gear 31 is fast to the platen shaft 11, and is of the same size and number of teeth as gear
 60 30; and the gear 32 is loose on the shaft 13 around which the platen swings, and has a face of sufficient width simultaneously to mesh with gears 30 and 31. A driving connection between the shaft 27 and the platen
 65 is thus maintained.

In the patent to Wernery and Smith, above referred to, it is shown that in the operation of removing a printed length of the web, and in readjusting the web for printing the next length, the platen is swung 70 up from printing position to a position away from the feed rolls, so that the web no longer wraps around the platen, but may be moved freely in substantially a straight line from the back to the front of 75 the machine. When the platen is in this position, the carbon sheets between the plies or folds of the section of the web to be removed, are drawn back into the length or section of web next to be printed; and, after 80 withdrawing a length of the web, the platen is returned to its normal position against the feed rolls.

The web is preferably in a single piece, fan-folded longitudinally, to provide for 85 several copies when carbon sheets are interleaved with the folds. It may also be in crosswise fan-folded condition before being fed into the machine to permit of compactness and convenience in handling, or it may 90 be fed from a roll. It is fed into the machine over a bar 33 at the rear of a table 34, shown as formed of tubing. The rear bar 33 is connected with a front bar 35 by side bars 36. The front bar 35 is mounted in 95 ears 39 on brackets 40 on the platen carriage. From the side rails 36 depend arms 43 carrying rolls 44 which ride and support the table on a rail 45, connected to the main frame of the machine. 100

The web is led across the table and over the front end thereof behind the platen, whence it is passed down between the platen and the pressure rolls, and thence up across the printing line at the type T, and onto a 105 paper shelf 48 forming part of the swinging platen frame carried by the arms 12. To the shelf 48 is secured a gage in the form of a bar 49, having adjustably mounted thereon a gage piece 50. The latter is a bent metal strip having openings through which the bar 49 passes, and having an offset portion against which the web can be drawn in measuring the length of the sheet to be cut from the web at the cutter 51. The cutter 110 is shown as a blade fast to a sleeve 52 which is loose on the shaft 13. A finger piece 53, also fast to the sleeve 52, is used to swing the cutter against the web when a measured length of the latter is to be removed. A 115 spring 54 holds the cutter in normal position away from the web, and returns the cutter to that position when the finger piece 53 is released.

When the platen is thrown up to release 120 the web, and the web is drawn forward to the gage piece 50, preliminary to cutting, the hold of the several parts on the web is released, with the consequence that the web in front of the platen may be rocked or 125 130

turned from true position, and may be cut other than squarely, or perpendicularly to the side edges of the web, unless care is used in alining the leading edge at the gage, or 5 unless some device is employed for assisting in positioning the web.

For this latter purpose there is secured to the under side of a brace or cross piece 55, on the swinging frame, a guide 56 which is 10 brought up and over the top of the paper shelf, and presents at the front of the latter a blade or guiding portion 57 (see Figs. 1 and 5) for the side edge of the web. The guide 56 has a hole through it to receive any 15 one of several screws 58, positioned at intervals along the brace 55, according to the width of web employed; and a thumb nut 59 threads onto the screws for detachably securing the guide in selected position. 20 Ears 60 on the guide, by engagement with the edge of the brace, prevent the guide from being tipped out of correct position, and aid in the proper setting of the guide.

It has been stated that the web is folded 25 longitudinally so that a plurality of copies may be made at a time by the use of carbon sheets. These carbon sheets, as above stated, are drawn back from the written portion of the web, into the length thereof next to be 30 written, at the time the web is released, and before it is cut. For permitting forward line-space feed of the carbon with the web, and for withdrawing the carbon sheets from the written to the next unwritten section of 35 the web, there is provided a carriage 61 to which the rear ends of the carbon sheets are attached. This carriage, (see Fig. 1) consists of a rectangular plate 66, having grooved rollers 64 which ride on rails 65 40 attached by screws to the tops of the side bars 36 of the table.

On the carriage 61, at each side thereof, is a stepped block 74. Fingers or clips 75, to each of which one carbon sheet may be 45 attached, are secured to the steps 76 of the blocks 74. The fingers 75 are staggered; alternate fingers being secured to the same side of the carriage, so that the fingers may lie in the oppositely directed fan-folds of 50 the web. The steps 76 space the several folds of the web so that the fingers which hold the carbon sheets may not bind the web. The web, therefore, as soon as it reaches the carriage 61 becomes interleaved 55 with the carbon sheets, the rear edges of which are held and the front edges of which are free, except that they are clamped between the folds of the web at the platen by the pressure rolls 15 and 16. Release of this 60 pressure, on lifting the platen, permits retraction of the carriage, with the carbon sheets, relatively to the web; and a handle 79 on the plate 66 serves as a means for throwing back the carriage 61. A suitable 65 stop may be provided for stopping the car-

riage at the proper position on each return throw of the same.

Side gages or guides for the web, in its passage across the table, are provided. One set of these is carried by the carbon holding 70 plate 66, and comprises L shaped members 94, the uprights 95 of which form the web guiding surfaces. These L shaped members are carried by and are preferably integral with strips or plates 96, slotted at 97 for the 75 passage therethrough of thumb screws 98, which are threaded into the backs of the stepped blocks 74. The screws 98 have shoulders 99 so that, by turning the screws in or out, the plates 96 may be clamped in 80 set position, or may be released to be slid on the blocks 74 to any setting according to the width of the web. Flanges 100 on the blocks support the lower edges of the plates 96 to maintain the guide pieces 95 in vertical 85 position. The plates 96 also have offsets 101 at their ends which by engagement with the sides of the blocks 74, prevent the plates 96 from being thrown inward against the screws 98 in such manner as to injure the 90 latter.

Another set of lateral guides or gages for the web is found on a bar 102 rigidly supported by arms 103 from the rear bar 33 of the table. These guides comprise upright 95 plates 104 and 105, each fast to a sleeve 106 slidable along the bar 102, (see Fig. 2). The bar 102, which is shown as a tube, is perforated at 107 at intervals therealong to receive locking pins 108 which are shiftable 100 in and out of the sleeves 106, and which, by projecting into the bar 102, hold the guides in place. Leaf springs 109 embrace the sleeves 106, and each has one end fixedly secured to the sleeve by a screw 110. The 105 springs are slotted circumferentially thereof at 111 for the passage therethrough of headed screws 112 carried by the sleeves. The heads of the screws 112 hold the underlying ends of the springs to the sleeves, but not 110 tightly enough to prevent free movement of the free ends of the springs circumferentially of the sleeve within the limits defined by the slots 111. The pins 108 also pass through circumferential slots in the springs, 115 and are grooved or shouldered to receive or engage the springs, so that when the pin is pulled out, the spring is drawn with it, within the limit defined by the slot 111 and screw 112; so that when the pin 108 is released, it is drawn inward by the spring, and by the latter is held in place in the selected hole 107.

The left-hand guide 105 has formed in conjunction therewith, a clamp which can 125 be turned down against the web to hold the web from slipping or being displaced when the carbons are being interleaved, or whenever the web is released from the platen and is not held by hand. This clamp consists 130

of a finger 113 horizontally offset from the 5 guide 105. The left-hand sleeve 106 is not only slidable along the bar 102, but may be turned thereon to bring the finger 113 to the web. The front of the bar 102, at the left-hand side of the table, is also perforated at points 114, so that when the finger 113 is 10 swung to web-engaging position it may be locked in such position by entry of the pin 108 in whichever of the holes 114 accords to the set position of the guide along the bar.

It will be seen that the guides 104 and 105 at the introductory side of the machine, the 15 guides 95 on the carbon-retracting carriage 61, and the guide 57 and gage 50 at the delivery side of the machine, jointly aid in properly guiding the web through the machine.

Variations may be resorted to within the 20 scope of the invention, and portions of the improvements may be used without others.

Having thus described my invention, I claim:

1. In a typewriting machine, a platen, 25 means for holding a web to the platen, means for releasing the web from the platen, a table over which the web is fed to the platen, and a device for holding the web when the latter is released from the 30 platen, said last-named device comprising also a guide for the edge of the web as the web is fed to the platen.

2. In a typewriting machine, a platen, 35 means for holding a web to the platen, means for releasing the web from the platen, and a shiftable device for holding the web against movement, or for guiding the web, according to the position to which said device is shifted.

3. In a typewriting machine, a platen, 40 means for holding a web to the platen, means for releasing the web from the platen, and a device having a web-guiding surface and a web-holding member, said device being movable from a normal web-guiding 45 position to a web-holding position.

4. In a typewriting machine, a platen, 50 means for holding a web to the platen, means for releasing the web from the platen, and a device having a web-guiding surface and a web-holding member, said device being pivotally mounted to be swung from a normal web-guiding position to a web-holding position.

5. In a typewriting machine, a platen, 55 means for holding a web to the platen, means for releasing the web from the platen, a device having a web-guiding surface and a web-holding member, said device being 60 pivotally mounted to be swung from a normal web-guiding position to a web-holding position, and a spring-controlled lock-pin for holding said device in either position.

6. In a typewriting machine, a platen,

means for holding a web to the platen, 65 means for releasing the web from the platen, and an arm normally acting as a web-guiding member but having an offset finger adapted to be swung against the web to hold the latter against movement. 70

7. In a typewriting machine, a platen, means for holding a web to the platen, means for releasing the web from the platen, a rod, a sleeve rockable on the rod, a web guide and holder carried by the sleeve, and 75 a pin carried by the sleeve adapted to be shifted into and out of perforations arranged at different angular positions in the rod for locking said sleeve with the guide in web-guiding position, and for locking 80 said sleeve after it has been turned on the rod to a web-holding position.

8. In a typewriting machine, a platen, means for holding a web to the platen, 85 means for releasing the web from the platen, a rod, a sleeve rockable on the rod, a web guide and holder carried by the sleeve, a pin carried by the sleeve adapted to be shifted into and out of perforations arranged at different angular positions in the rod for 90 locking said sleeve with the guide in web-guiding position, and for locking said sleeve after it has been turned on the rod to a web-holding position, and a spring carried by 95 said sleeve for holding the pin in either locking position.

9. In a typewriting machine, a platen, a table over which a work-piece is fed to the platen, a device movable into and out of engagement with the work-piece on the 100 table for holding the work-piece against displacement thereon, or for releasing the work-piece to permit feed of the same, according to the position of said device, and means for adjusting the setting of said device for work-pieces of different widths. 105

10. In a typewriting machine, a platen, a table over which a work-piece is fed to the platen, a device movable into and out of engagement with the work-piece on the table 110 for holding the work-piece against displacement thereon, or for releasing the work-piece to permit feed of the same, according to the position of said device, and means for adjusting the setting of said device for work- 115 pieces of different widths, said device comprising also a guide for the side edge of the work-piece.

11. The combination with a platen, of 120 means for feeding a work-piece in a plurality of plies to the platen, a table over which the work-piece is fed to the platen, a carriage movable on said table and toward and away from the platen, means on the carriage for holding transfer material between 125 the plies of the work-piece as the latter is fed to the platen and for shifting the transfer material backward along the work-piece

to successive placements thereon, a guide on said carriage, for the side edge of the work-piece, having a screw-and-slot connection to the carriage so that it may be set thereon for work-pieces of different widths, means coöoperating with said screw to lock the guide in set position, and a stop for prevent-

ing the end of said slot from striking the threads of said screw when the guide is shifted.

BENJAMIN P. FORTIN.
